UNITED STATES PATENT OFFICE

2,640,686

HEAT EXCHANGE TYPE OF TANK HEATER

John W. Brown, Jr., Lakewood, Ohio, assignor to
 Brown Fintube Company, Elyria, Ohio, a corporation of Ohio

Application August 30, 1949, Serial No. 113,224

2 Claims. (Cl. 257—198)

1

This invention relates to heat exchangers and more particularly to heat exchangers adapted to heat liquids within large tanks.

In the storage of viscous liquids, it is frequently necessary to provide heating means in the storage tanks to heat the contents so that the viscosity of the liquids will be reduced to a point at which the liquids will flow readily and at which they can be pumped easily. It has been the practice heretofore to install horizontally extending heat exchanger tubes near the bottom of the tanks in order to accomplish this purpose. Such installations are open to objection in several respects: the repair and replacement of the tubes is difficult; the efficiency of the heat exchangers is not initially high and is further reduced in service by the accumulation of sediment on the tubes; and each installation has to be individually designed and constructed for the particular job.

A general object of the present invention is to provide heat exchangers particularly adapted for use in tanks in which the above noted difficulties are eliminated. More specifically, it is an object of the invention to provide tank heaters which can be installed readily and economically in tanks of various sizes and constructions and which can easily be removed and replaced through a standard manway. Another object is the provision of such heaters in which the heat exchange tubes are mounted vertically to eliminate fouling of the tubes and to increase the efficiency of heat transfer by reason of thermosyphon flow or circulation within the tanks and along the vertically extending heat exchanger tubes. Another object is to provide a heat exchanger which can readily be connected to steam and condensate manifolds or pipes disposed outside of the walls of the tank.

Further objects and advantages of my invention will become apparent from the following description of a preferred form thereof, reference being made to the accompanying drawings, in which Figure 1 is an elevation partly in section showing a typical installation of my tank heaters in a large storage tank; Figure 2 is a plan view of the tank shown in Figure 1 with the top or cover removed; Figure 3 is a vertical sectional view on an enlarged scale illustrating one of the heaters of Figure 1 with parts broken away to show the construction of the preferred tank wall fitting; and Figure 4 is a plan view of the heater shown in Figure 3.

A typical installation of tank heaters embodying the present invention as applied to a large tank indicated in general at 10 is shown in Fig-

2

ure 1 of the drawings. This tank, which may be of the type utilized for storage of heavy oils or viscous chemicals, has a bottom 10, a cylindrical side wall 11 and a domed top 12. In order to heat the contents of the tank, a number of heaters embodying the present invention and indicated in general at 15 are disposed within the tank. As shown in Figure 2, the heaters are positioned near the tank wall 11 and are uniformly spaced apart around the tank. The heaters are connected to the steam manifold 16 through exterior connecting pipes 17, wall joint fittings 18 and interior connecting pipes 19. The bottoms of the heaters are connected to a condensate manifold 20 through exterior connecting pipes 21, wall joint fittings 22 and interior connecting pipes 23. Pedestals 24 support the heaters above the floor 10 of the tank.

In order to provide a large amount of heat transfer surface in a relatively small space, each heater, as shown particularly in Figures 3 and 4, is made up of two concentric rows of vertically extending externally finned heat exchanger tubes. The tubes in the outer row are indicated by reference character 26, and the tubes in the inner row by reference character 27. All of these tubes preferably are provided with a plurality of longitudinally extending external fins 29 in accordance with the teachings of my prior Patents Nos. 2,261,136 and 2,261,137. These fin members give each tube greatly extended surface area in contact with the commodity within the tank, and because of their vertical arrangement, they create upward flow of the commodity along the longitudinally extending fins, thus creating a general circulation of fluid in the tank upward around the outer wall of the tank in the zone of the heaters and downward in the center of the tank. The circulation so obtained greatly increases the efficiency of heat transfer of the vertical tubes as compared with horizontally disposed tubes, and furthermore the vertical mounting practically eliminates deposition of sediment on the tubes and insures maintenance of the original efficiency of the heaters throughout long periods of time.

In order to supply heating medium to the tubes, the tubes 26 and 27 are connected at their upper ends to a top header 31, the header being connected in turn to the inner supply pipe 19. The connections between the tubes 26 and the header 31 are made by welding the ends of the tubes, which are not finned, into apertures in the bottom of the header as shown at 32. The tubes 27 are secured to horizontal apertures in

the header 31 by bending the unfinned end portions of the tubes as shown at 33 and welding them within the horizontal apertures as shown at 34.

Similar connections are made at the bottom of the exchanger, the bottom header 36, which is connected to the interior condensate pipe 23, being welded to the extensions of the tubes 26 as indicated at 37 and to the curved extensions 38 of the tubes 27 as indicated at 39.

In order to support the heaters within the tank, a pedestal 24 is disposed beneath each heater. Each pedestal is made up of telescoping tubes 41 and 42 welded together as at 43 to provide a pedestal of the required height for the particular installation. The tube 41 rests on the bottom 10 of the tank while the tube 42 engages a plate 44 which in turn supports the bottom header 36.

In order to connect the inner connecting pipes 19 and 23 with the outer connecting pipes 17 and 21, respectively, through the wall of the tank, fittings 18 and 22 are provided. These are preferably of identical construction, and hence only the fitting 18 will be described herein.

In order that the connections may be made exteriorly of the tank, I preferably employ tubular connections of the general type shown and claimed per se in my Patent No. 2,449,052, issued September 14, 1948. By means of this type of connection a heater is readily installed by inserting the heater through the manway into the tank and then passing the connecting pipes 19 and 23 outwardly through apertures in the tank wall to join the corresponding pipes.

To provide this connection, a flanged tank fitting 45 is welded to the tank wall 11 at the aperture 46 through which the pipe 19 extends. Pipe 19 is provided at its end with an enlarged flange portion 47 which passes through and extends exteriorly beyond the tank fitting 45. The pipe is secured to the fitting by means of a split locking ring 48 which is seated within a groove 53 in the flange portion 47 and which engages an outwardly facing shoulder 54 within the tank fitting 45. Inward movement of the pipe relative to the tank fitting is thus effectively prevented. In order to provide a seal between the pipe 19 and the tank fitting 45 a sealing ring or gasket 49 is drawn into sealing engagement against conical sealing surfaces 55 and 56, of the pipe flange portion 47 and the tank fitting 45 respectively, by a compression ring 50. The ring is pulled tightly against the gasket 49 by securing screws or studs 51 which extend through the ring and which are threaded into the flange of the tank fitting 45. When the screws 51 are drawn tight the pipe 19 will be held securely against the tank fitting 45 and an effective seal will be provided by the gasket 49 so that the contents of the tank will not leak at this point.

The connection to the external connecting pipe 17 is made by providing the external pipe or conduit 17 with an enlarged end 58 having a shoulder 59 which is engaged by the collar 60. Screws or studs 61, extending through openings in the collar 60 and in the ring 50 and threaded into the flanged tank fitting 45, urge the collar 60, and hence the enlarged end portion 58 of pipe 17, toward the tank and bring the end portion 58 into sealing engagement with the enlarged end 47 of pipe 19. A gasket 62 is disposed between the opposed surfaces of the parts 47 and 58 to effect a seal between the pipes.

By this arrangement and the similar arrangement at the bottom of the heater, a simple leak-

proof joint can be made between the connecting pipes and tank wall. The pipes 17 and 21 leading to the manifolds can be disconnected from the pipes 19 and 23 without disturbing the connections between the tank wall and the pipes 19 and 23. All connections can be made and broken from the exterior of the tank and can be readily inspected. Any leakage of the joints will be evident from the exterior of the tank. Thus, in-

10 stallation of the heaters and maintenance is facilitated because any individual heater can be disconnected from the manifold and readily removed from the tank for inspection or repair, independently of and without interfering with 15 the installation and operation of the other heaters.

From the foregoing description of a preferred form of my invention it will be evident that I have provided a simple and highly efficient tank heater. Because my heaters are made in units, 20 heaters of the same construction can be adapted to a wide variety of uses. A single heater may be employed in a small tank; larger tanks may require two or three heaters; and still larger tanks may require a greater number of heaters. However, all installations can be made in substantially the same manner and with parts of 25 generally similar or standard construction, thus making for economy of construction and installation.

Because of the efficiency of the vertical installation and of the finned tube heat exchange elements, my heaters are very compact for their capacity. My standard heaters are made with 30 an overall diameter such that they can be installed in and removed from a tank through a standard 20 inch manway. The comparatively small size of the units makes them easy to handle as compared to single large heater installations 35 of the prior art. The efficiency of the heaters is such that they displace a small volume of fluid within the tank and hence do not greatly reduce the storage capacity of the tanks within which they are installed. Because the heaters are made in units, they can be installed easily in new or 40 existing tanks, and units can be added or removed in accordance with the changing requirements of service.

Those skilled in the art will appreciate that 45 various changes and modifications can be made in my invention without departing from the spirit and scope thereof. For example, instead of the two concentric rows of finned tubes shown in the drawings, three rows or only one row may be 50 employed, and a different type of tank wall fitting such as that shown in my Patent No. 2,424,221 may be utilized if desired. Therefore, it is to be understood that my invention is not limited to the preferred form disclosed herein and that 55 the scope of the invention is defined by the appended claims.

I claim:

1. In combination with a tank, a heater disposed within the tank and spaced from the side wall and bottom thereof, said heater being small as compared with the tank and comprising an annular upper header, an annular lower header, a plurality of heat exchange tubes having longitudinal external fins thereon extending substantially vertically between the headers, adjacent tubes being spaced sufficiently so that the fins thereon do not overlap, said headers and said heat exchange tubes being in direct contact with the main body of material within the tank, the longitudinal fins on said heat exchange tubes

providing substantially unobstructed paths for the flow of the material within the tank along said fins and tube in vertical directions, an upper connecting pipe and a lower connecting pipe connected to said headers respectively and extending laterally from said headers through the wall of said tank, and fittings for said upper connecting pipe and said lower connecting pipe, each of said fittings making sealing engagement between its respective pipe and the wall of the tank.

2. In combination with a generally cylindrical tank adapted to contain a commodity to be heated, a plurality of circumferentially spaced heaters within the tank, said heaters being spaced from the side wall and bottom thereof, the heaters being small as compared to the tank, each heater comprising an annular upper header and an annular lower header and a plurality of vertically disposed heat exchange tubes having longitudinal external fins thereon extending between said headers, adjacent tubes being spaced sufficiently so that the fins thereon do not overlap, said headers and said heat exchange tubes being in direct contact with the main body of the commodity within the tank, the longitudinal fins on said heat exchange tubes providing substantially unobstructed paths for the flow of the commodity within the tank along said fins and tube in vertical directions, an upper connecting pipe and a lower connecting pipe connected to
